WOVEN SCREEN OR SIMILAR ARTICLE

Stanley E. Waite, Oshkosh, Wis., assignor to
Waite Carpet Company, Oshkosh, Wis., a cor-
poration of Wisconsin

Application January 7, 1950, Serial No. 7,068

Term of patent 14 years

(Cl. D92—4)

To all whom it may concern:

Be it known that I, Stanley E. Waite, a citizen of the United States, residing at Oshkosh, in the county of Winnebago and State of Wisconsin, have invented a new, original, and ornamental design for a Woven Screen or Similar Article, of which the following is a specification, reference being had to the accompanying drawing, forming part thereof, wherein—

Figure 1 is a perspective view of a woven screen or similar article, showing my new design; and

Fig. 2 is a fragmentary close-up view of a portion of the woven screen or similar article at the juncture of four blocks comprised in its pattern, showing also a dowel pin disposed in coincidence with a juncture line extending vertically between the blocks.

I claim:

The ornamental design for a woven screen or similar article, as shown and described.

STANLEY E. WAITE.
